Primary Examiner — Kevin Rudzinski(74) *Attorney, Agent, or Firm* — Gifford, Krass, Sprinkle, Anderson & Cikowski, P.C.(57) **CLAIM**

The ornamental design for a box compact, as shown and described.

DESCRIPTION

FIG. 1 is a rear side view of box compact, showing my new design in a fully closed position;

FIG. 2 is a front side view thereof;

FIG. 3 is a front top perspective view thereof;

FIG. 4 is a rear top perspective thereof;

FIG. 5 is a front top perspective view thereof, in an open lid position;

FIG. 6 is a front top perspective view thereof in an open lid position and with an extended insert compartment;

FIG. 7 is a first side view thereof in a fully closed position;

FIG. 8 is a second side view thereof; and

FIG. 9 is a top view thereof;

FIG. 10 is a bottom view thereof; and,

FIG. 11 is a a is an open side view of the second side thereof in an open lid position and with an extended insert compartment, with an open side view of a first side a mirror image thereof.

The broken lines shown in the drawings illustrate portions of the box compact that form no part of the claimed design.
